DRAWER FOR A CARD CATALOG CABINET

Jens Risom, New Canaan, and Carl Jacobs, Old Greenwich, Conn. (both of 444 Madison Ave., New York, N.Y. 10022)

Filed May 16, 1967, Ser. No. 7,147

Term of patent 14 years

(Cl. D33—1)

FIG. 1.

FIG. 2.

FIG. 3.

FIG. 4.

FIG. 5.

FIG. 1 is a perspective view looking from the front and top of the drawer for a card catalog cabinet embodying my new design;

FIG. 2 is a side elevational view looking at the left of the drawer, as shown in FIG. 1;

FIG. 3 is a top plan view looking down on the drawer; FIG. 4 is a front elevational view of the drawer; and FIG. 5 is a rear elevational view of the drawer.

We claim:

The ornamental design for a drawer for a card catalog cabinet, as shown.
